A. C. GUNDY.

IGNITION SYSTEM FOR INTERNAL COMBUSTION ENGINES.

APPLICATION FILED JUNE 15, 1912.

1,096,625.

Patented May 12, 1914.

UNITED STATES PATENT OFFICE.

ALTON C. GUNDY, OF UPLAND, CALIFORNIA, ASSIGNOR OF ONE-HALF TO M. H. HAY,
OF LOS ANGELES, CALIFORNIA.

IGNITION SYSTEM FOR INTERNAL-COMBUSTION ENGINES.

1,096,625.

Specification of Letters Patent. Patented May 12, 1914.

Application filed June 15, 1912. Serial No. 703,983.

To all whom it may concern:

Be it known that I, ALTON C. GUNDY, a citizen of the United States, residing at Upland, in the county of San Bernardino and State of California, have invented a new and useful Ignition System for Internal-Combustion Engines, of which the following is a specification.

This invention relates to a system for generating electric sparks in the cylinders of an internal combustion engine and effect the ignition therein, and the main object of the invention is to provide for a uniform period of closure in the circuit controlling means for the sparking circuits, irrespective of the speed of the engine.

A further object of the invention is to provide for the break required for the generation of the sparking impulse without the use of a vibrator.

Other objects of the invention will appear hereinafter.

The accompanying drawings illustrate the invention, and referring thereto:—

Figure 1 is a front elevation of the circuit controlling means for the system, with a diagram of the circuit connections constituting the igniting system. Fig. 2 is a perspective of the circuit controller. Fig. 3 is a perspective of the interlocking means of the circuit controller showing one position thereof. Fig. 4 is a similar view showing another position of the interlocking means. Fig. 5 is a plan showing the position of the parts in Fig. 3. Fig. 6 is a plan showing the position of the parts in Fig. 4.

The invention is illustrated in connection with a system adapted for a four-cylinder engine, but it will be understood that it is applicable in connection with any multicylinder engine, proper changes being made in the construction.

The distinguishing feature of the invention is an automatic circuit controller connected in the circuit which on closure of the circuit by the timer to the sparking circuit of any one of the cylinders automatically opens said circuits and establishes a connection to the circuit for the next cylinder in advance. The circuit controller comprises two electromagnets 1 and 2 mounted on a suitable base or support 3, and armatures 4

and 5 for the respective electromagnets, said armatures being carried respectively by springs 6 and 7, each fixed at one end to a bracket 8 on the base 3 and provided at its other end with a contact 9 or 10 adapted to make contact when the armature is attracted to the magnet with a fixed contact 11 or 12. The said armature springs 6 and 7 tend to 60 spring away from the cores of the respective electromagnets 1 and 2 and are provided with interlocking means whereby each spring, as it moves away from the magnet, locks the other spring in position toward the 65 other magnet so as to maintain closure of the contact controlled by said other spring and as each armature is attracted by its magnet, the corresponding spring allows the other spring to be released and to move out 70 of circuit closing position. For this purpose, spring 7 has a notch 14 in its upper edge and the outer end portion of the spring 6 is cut away at its lower edge leaving an extension 6' which extends through the said 75 notch 14 and said spring 6 being further provided with a lateral projection or shoulder 16 adapted to engage with the outer side of the spring 7 at the outer edge of the notch 14 therein, said portion of the spring 7 80 forming a shoulder 16' to hold said spring 7 toward its magnet 2 when the spring 6 is away from its magnet 1. The said outer edge of the notch 14 in spring 7 engages with the outer face of said projection or 85 shoulder portion 16 on the spring 6 when the spring 7 is away from its magnet 2.

The connections may be as shown in Fig. 1, where 18 designates the central contact of a timer mechanically connected to be rotated 90 by a shaft of the engine from which the sparks are to be produced, and 19 the member carrying the fixed contacts 20, 21, 22 and 23 of the timer connected by wires 25 to the primary windings of the respective induction coils 26, 27, 28 and 29, whose other ends are connected to the magnets 1 and 2, the connection being such that the primary coils are connected to said magnets in two groups, magnet 1 being connected to one group of 100 said coils and magnet 2 being connected to the other group. For this purpose alternate primary coils 26 and 28 are connected by wires 30 to a wire 31 leading to the magnet

1 and the intermediate primary coils 27 and 29 are connected by wires 32 to a wire 33 leading to magnet 2. The other terminals of the magnets 1 and 2 are connected respectively by wires 34 and 35 to the respective fixed contacts 12 and 11, the contact springs 6 and 7 being connected respectively by wires 36 and 37 and to a wire 38 leading to one side of battery 39, the other side of said battery being grounded or connected by connection 40 to the central rotating contact 18 of the timer. The secondary windings of the respective induction coils 26, 27, 28 and 29 are connected to high tension sparking circuits 41, 42, 43 and 44 containing spark gap means 45 for effecting ignition in the engine cylinders in the usual manner.

The operation is as follows: When in the rotation of the timer, an operative connection is established from the battery through wire 40 and rotary contact 18, contact 20, wire 25 to the primary of induction coil 26, wire 30, wire 31 to electromagnet 1, thence by wire 34, contacts 12 and 10, contact spring 7, wires 37 and 38 back to the battery. At the moment when this connection takes place, the electromagnet circuit controller is in position shown in Fig. 1 with the armature spring 6 retracted, opening the circuit at contact 11; and armature spring 7 held toward its magnet by engagement of the shoulder 16 on spring 6 with the portion 16' of the spring 7, thereby holding the contact closed at 12 and the circuit above traced to be established. When current flows as above stated, the resulting energization of magnet 1 causes the armature 4 thereof to be attracted drawing the contact spring 6 into contact with the fixed contact 11 and moving the shoulder 16 on the contact spring 6 away from the engaging portion 16' of the contact spring 7 and allowing said contact spring 7 to spring away from its magnet by its own elasticity and to open circuit at contact 12. This opening of circuit at contact 12 opens the energizing connection for the magnet 1, but it will be observed that the same movement of the contact spring 7 brings the shoulder portion 16' thereon back of the shoulder portion 16 on the contact spring 6, thereby holding said contact spring 6 into contact with the fixed contact 11 and maintaining a connection for the other group of primary coils so that when in the operation of the timer the rotative contact thereby makes contact with the next contact 21 which belongs to said other group, an energizing connection will be established for the primary winding of the induction coil 27 in said other group and also for energization of the other magnet 2. This next action of the timer in making contact with the contact 21 completes the circuit and energizes the primary winding of the induction coil

27 and the magnet 2, the current passing 65 from battery 39 through wire 40, contacts 18 and 21, wire 25, primary winding of induction coil 27, wires 32 and 33 and magnet 2 to contact 11, thence through contact spring 6 and wires 36 and 38 back to the 70 battery 39. Contact spring 7 is thereby attracted by magnet 2 and caused to close circuit at contact 10 and at the same time the shoulder 16' on said contact spring 7 is moved out of engagement with the shoulder 75 16 on contact spring 6 allowing the contact spring 6 to be moved by its own elasticity to open contact 11 and to spring back of the contact spring 7 to retain said contact spring 7 in closed position. This restores the original 80 position of the circuit controller and brings the circuit again in position for operation of the timer on a primary coil of the first group, this operation being repeated indefinitely. The effect of energization of 85 either magnet 1 or 2 is to open the circuit of that magnet, this circuit also including the primary of one of the induction coils in the corresponding group and when the circuit of the induction coil is open in this 90 manner, a high tension discharge will be produced in a secondary winding and circuit of that coil, resulting in a discharge or spark across the electrodes or spark gap means 45.

What I claim is:

1. In an ignition system comprising a plurality of sparking circuits, a timer for establishing connections successively to said circuits and a source of current, a circuit controller adapted to shift the connection 100 from a source of current successively to different sparking circuits controlled by the timer, said circuit controller comprising two contact devices, electromagnets respectively controlling said contact devices, circuit connections connecting the respective electromagnets and contact devices in circuit with different groups of sparking circuits, said contact devices being provided with mechanical interlocking means constructed to lock 110 each of said contact devices in closed position by engagement with the other contact device when the latter is in open position.

2. In an ignition system, the combination of a plurality of igniting circuits and their energizing connections, means for shifting the connections successively to the energizing connections for the different igniting circuits comprising two electromagnets connected respectively in said energizing connections, contact means operated by each of said electromagnets and controlling the energizing connection for the other of said electromagnets, each of said contact means tending to move to position to open the circuit 120 of the other electromagnet and each of said electromagnets acting on said contact means to close the circuit of the other electromag-

net, and said contact devices being provided with mechanical interlocking means constructed to lock each of the contact devices in closed position by the action of the other contact device when said other contact device is in open position.

In testimony whereof, I have hereunto set

my hand at Upland, Cal., this eighth day of June 1912.

ALTON C. GUNDY.
